(57) **CLAIM**

The ornamental design for pants with right side pocket for cell phone, as shown and described.

DESCRIPTION

FIG. 1 is a front elevation view of pants with right side pocket for cell phone showing our new design.

FIG. 2 is a back elevation view of the pants with right side pocket for cell phone.

FIG. 3 is a right side elevation view of the pants with right side pocket for cell phone.

FIG. 4 is a left side elevation view of the pants with right side pocket for cell phone; and,

FIG. 5 is a bottom plan view of the pants with right side pocket for cell phone.

The broken lines shown on the surface of the pants in FIGS. 1-5 represent stitching.
